UNITED STATES PATENT OFFICE

WALTER S. FISHER, OF TOLEDO, OHIO, ASSIGNOR TO THE WILLYS-OVERLAND COMPANY,
OF TOLEDO, OHIO, A CORPORATION OF OHIO

FIXTURE FOR EXPANDING PISTONS

Original application filed July 10, 1923, Serial No. 652,302. Divided and this application filed June 19, 1926. Serial No. 117,057.

This invention relates to jigs or work-holders and more particularly to work-holders adapted to dimension the exterior of expandable pistons, the present application being a division of my copending application for Letters Patent Serial No. 652,302 filed July 10, 1923.

One of the objects of the invention is to provide a work-holder for an expandable piston that will hold the piston skirt to a predetermined maximum diameter during the fitting of an expanding member.

Another object of the invention is to provide a work-holder for an expandable piston that will enable a workman to insert a piston in the holder, force an expanding member into the piston for expanding the same to a predetermined diameter and hold the member in the piston at the desired expansion until permanent securing means are installed.

A further object of the invention is to provide a work-holder for an expandable piston in which the piston may be expanded and permanently secured against contraction, without involving a great amount of physical and mental work.

A disclosure constituting one embodiment of the invention is illustrated in the accompanying drawings, in which

Figure I is a sectional elevation through the holder and a piston showing the means for expanding the piston, the section being taken on line I—I of Fig. II.

Fig. II is a top plan view of the holder and piston shown in Fig. I.

Fig. III is a sectional plan view taken on line III—III of Fig. I.

Fig. IV is a detail perspective view of the expandable ring shown in Figs. I, III and VIII.

Fig. V is a detail view taken on line V—V of Fig. VII.

Fig. VI is a detail view taken on line VI—VI of Fig. VIII.

Fig. VII is a slightly enlarged fragmentary section of the lower end of the piston with the reinforcing parts removed.

Fig. VIII is a slightly enlarged section of a portion of an engine cylinder containing a

piston which has been expanded by means of the improved holder.

Referring to the drawings in which like characters refer to like parts throughout the views, 1 generally denotes the improved holder which is provided with a cylindrical bore 2 of a predetermined size, preferably a size substantially equal to the desired external diameter of an expanded piston. Fig. I illustrates a piston 3 of a well-known type within holder 1, and upon which the several operations necessary to the expansion have been completed. Piston 3 is provided with a skirt portion 4 which is expandable because of a slot 5, extending longitudinally thereof from a transverse slot 6 to the open end of the skirt. Within the skirt 4 and preferably near the open end thereof, is an annular groove 7 and a recess 8. An expandable ring 9 is adapted to be inserted in the groove 7 and expanded by means of wedge 10 inserted between the open ends of the ring 9 and subsequently secured in position within recess 8 by means of rivet 11.

Holder 1 is provided with aligned radial openings 12 of substantially the same diameter as the piston pin holes 13 in piston 2, and an extension 14 in which is threaded a screw 15 having a face 16 adapted to overlap the holder bore 2. A radial hole 17 extends from the exterior of the holder to the bore 2 so as to have its internal opening substantially intersect the axis of screw 15, screw 15 being so located that it will be above the recess 8 in piston 3 during the expanding operation.

In the operation of the holder, a piston 3 is inserted therein, with its recess 8 in substantial alignment with hole 17, and its piston pin holes 13 in alignment with openings 12. A pin 18 is inserted in the aligned holes 12. A ring 9 is then inserted in groove 7 with its ends lying within recess 8, a wedge 10 is inserted between the ends of ring 9 and pressure applied thereto by means of screw 15, until the ring and the skirt 4 have been expanded to the desired di-

mension, which will ordinarily be the bore of the holder. A hole is then drilled through skirt 4 and wedge 10 by means of a drill (not shown) being inserted in hole 17, and the wedge is securely fastened in position by rivet 11. Both the drilling and riveting operations are performed with the piston parts held in position by screw 15, after which the screw is released, pin 18 is withdrawn, and the finished piston removed from the holder.

While the construction herein shown and described is well adapted to fulfill the objects of the invention, it is to be understood that changes in the form, proportions, arrangement of parts and details of construction shown, may be resorted to when found expedient, without departing from the spirit of the invention as expressed in the claims.

20 I claim:

1. A holder for expandible pistons adapted to form a gauge for controlling the diameter of the piston, means for securing the skirt portion of the piston within the holder, and means associated with the holder for effecting expansion of the piston to the limits of the gauge.

2. A holder for expandible pistons having a bore corresponding to a predetermined diameter of a piston; said holder having an opening; means extending in said opening for holding said piston in position; and means cooperatively disposed with respect thereto for expanding the piston to a diameter of the bore.

3. A holder for expandible pistons having a bore corresponding to a predetermined diameter for the piston, said holder having an opening therein, a piston securing pin adapted to extend through said opening into the wrist pin bore of the piston, whereby to secure the piston within the holder, and means associated with the holder for effecting movement of an expanding member adapted to expand the piston to the limits of said bore.

4. A holder for expandible pistons having a bore corresponding to a predetermined diameter of a piston, means for holding a piston against movement within said bore, and movable means on said holder having a portion overlapping said bore and adapted to engage expanding means within said piston, whereby said movable means is enabled 55 to cooperate with the expanding means for causing said piston to expand to the limits of said bore.

5. A holder for expandible pistons having a bore corresponding to a predetermined 60 diameter of a piston, means for holding a piston against movement within said bore, movable means on said holder having a portion thereof overlapping said bore and adapted to engage expanding means within said 65 piston for expanding the same to the limit

of said bore, said holder being provided with an opening adjacent the skirt of the piston and substantially in line with said expanding means wherein a tool may be inserted for forming an opening in said piston and said expanding means.

In testimony whereof, I affix my signature.

WALTER S. FISHER.
